F. A. STEVENS.

LACING TIP.

APPLICATION FILED JAN. 16, 1918.

1,263,716.

Patented Apr. 23, 1918.

Inventor:
Frederick A. Stevens

By Norbert E. Belloni
Attorney:

UNITED STATES PATENT OFFICE.

FREDERICK A. STEVENS, OF PROVIDENCE, RHODE ISLAND.

LACING-TIP.

1,263,716.

Specification of Letters Patent. Patented Apr. 23, 1918.

Application filed January 16, 1918. Serial No. 212,126.

To all whom it may concern:

Be it known that I, FREDERICK A. STEVENS, a citizen of the United States, residing at Providence, in the county of Providence and State of Rhode Island, have invented certain new and useful Improvements in Lacing-Tips, of which the following is a specification.

My invention relates to shoe laces, corset 10 laces and the like, and more particularly to the tips or insertible ends thereof.

The essential objects of my invention are to provide a stiff lace end adapted for facile insertion into eyelets; to prevent fraying 15 or raveling of the lace covering; to insure against accidental removal or loss; and to present to the eye a minimum of metal without sacrificing the stiffness and rigidity necessary for facile insertion; also cheapness 20 of construction.

To the accomplishment of the recited objects and others coördinate therewith, the preferred embodiment of my invention resides in the construction and arrangement 25 shown in the accompanying drawings, hereinafter described, and embraced in the scope of the appended claims.

In said drawings, which form a part of this specification,

30 Figure 1 is a longitudinal section, partially in side elevation, of a length of lacing material in its initial stage of construction, constituting the core,

Fig. 2, a side elevation of the same including the fabric covering,

Fig. 3, a like elevation of a shortened length of the same,

Fig. 4, a similar view of said length provided with tips and constituting the completed lace, and

Fig. 5, a longitudinal section of one of the tips.

Like reference characters indicate like parts throughout the views.

45 The construction of my device is as follows: Several fabric threads or strands *a* are assembled in contact and parallelism with each other forming a body *A*. At suitable intervals the strands are tightly embraced or clamped by a sleeve *B* of stiff or comparatively non flexible material, preferably of fiber or metal. In the present instance the binding members are strips of metal bound tightly around the body with

their edges in contact or overlapping to 55 form a longitudinally split sleeve. The member thus far described, and shown in Fig. 1, constitutes a core or body over which is braided or woven a tubular fabric covering *C*, as shown in Fig. 3.

60 The described strip is now transversely severed at some point intermediate the length of the sleeve *B*. The separation is so made that at each end of the resultant length there shall be a substantial portion 65 of the stiff element *B*.

A cap or ferrule *D* of less length than the member *B* comprises a side wall *d* and an end wall *e*. This is next applied at each 70 end of the length by swaging or otherwise forcing the side wall *d* thereof into the covering *C* so that the retracted or projecting portion *f* of the wall forms an indentation *g* in the covering and a corresponding indentation *h* in the member *B*, thus making 75 removal difficult. The final form of the end *e* of the cap is preferably conical to facilitate insertion.

I claim:

1. In a lacing, the combination of a flexible body, rigid sleeves upon the ends of the body, a continuous tubular textile inclosing both the body exterior of the sleeves and the sleeves, and ferrules of less length than the sleeves embracing the sheath and sleeves. 80 85

2. In a lacing, the combination of fabric strands, rigid sleeves, spaced from each other on the strands and provided with depressions, a tubular textile sheath embracing the strands exterior of the sleeves and the sleeves, ferrules on the ends of the sheath, and projections on the ferrules registering in the depressions in the sleeves. 90

3. The process of making a lacing consisting in assembling a plurality of fabric strands in a body of indefinite length, clamping around upon the body thus assembled at regular intervals rigid sleeves, next surrounding the body between the sleeves and the sleeves themselves in a continuous textile sheath, next transversely severing the described member at intermediate portions of the sleeves, and finally clamping ferrules over the ends of the severed portions. 95 100 105

In testimony whereof I have affixed my signature.

FREDERICK A. STEVENS.
